UNITED STATES PATENT OFFICE

VERNON ANTHONY TRIER, OF LONDON, ENGLAND

ELECTRIC SWITCH

Application filed September 7, 1927, Serial No. 218,031, and in Great Britain September 17, 1926.

This invention relates to electric switches of the kind comprising two disc-like or annular contact members arranged in parallel planes one above the other, one of these contact members being mounted on a resilient support which enables it to be rocked so as to make contact with the other contact member. The object of the invention is to provide an improved switch of the above type particularly but not exclusively applicable to the horn circuit of a motor road vehicle and adapted to be operated, for example, by depressing an auxiliary wheel rim mounted adjacent to and concentric with the rim of the steering wheel of the vehicle.

According to the present invention the flexible support for the movable contact member is formed of rubber or other resilient insulating material which will normally maintain the two contact members apart but will enable one of such members to be rocked into engagement with the other when the switch is to be closed. Thus the rubber or like member serves both as an insulator between the contact members and as a spring tending to separate the two contact members.

The invention may be carried into practice in various ways but three alternative constructions of switch according to this invention suitable for closing the horn circuit of a motor road vehicle are illustrated by way of example in the accompanying drawings, in which

Figure 1 is a side elevation partly in section showing one form of switch secured to the vehicle steering wheel,

Figure 2 is a section on an enlarged scale through the annular contact members and resilient insulating member constituting the switch shown in Figure 1,

Figure 3 is a side elevation partly in section showing an alternative form of switch according to this invention as applied to a steering wheel,

Figure 4 is a longitudinal section through the switch shown in Figure 3,

Figure 5 is an elevation partly in section of another alternative form of switch, and

Figure 6 is a section on an enlarged scale

through the fixed and movable members constituting the switch shown in Figure 5.

In the construction illustrated in Figures 1 and 2 the switch comprises an annular inner contact member A adapted to be secured to the vehicle steering wheel B by means of clips or the like C. Surrounding the upper portion of the member A and formed so that it extends inwards over the upper edge of this member is an outer annular contact member D. Formed in the portions of the contact members A and D which overlap are grooves A¹, D¹ which together form an annular recess between the two contact members in which is accommodated a tubular rubber or like resilient insulating member E. The member E thus serves not only to insulate the contact members from one another and normally to maintain the contact member D out of engagement with the contact member A but also to prevent the contact member D being detached from the contact member A. It will thus be seen that the annular member E is held under compression in the recesses in the members A and D and serves as the sole operative connection between these parts to prevent their being completely separated, yet allow further compression when one contact member is rocked into engagement with the other.

The contact member A may if desired be provided with contact points A² on its upper edge as shown to ensure proper contact being made with the contact member B while terminals A³, D² are conveniently provided respectively on the contact members A and D for connecting these members respectively to one of the horn terminals and one of the battery terminals.

In the construction shown in Figures 1 and 2 the member E is conveniently formed as a plain length of tubing and the contact members A and D and member E may be assembled by stretching the tube E tightly around the groove A¹ in the inner contact member A so that this tube is flattened, the ends of the tube being drawn through two holes A⁴ passing radially through the contact member as shown. The lower edge of the contact member D is then passed over

the contact member A and tube E into position, soap or other suitable substance being employed if necessary to ease the member D over the tube E. When the contact member D is in position over the contact member A, the ends of the tube E are released whereupon the tube contracts in length and expands laterally into contact with the groove D¹ in the outer contact member D.

10 If after the ends of the tube have been released, these still project through the holes A⁴, they may be cut off.

Alternatively to the above method of assembling the parts of the switch, the following method may be employed, the rubber tube E in this case being formed either as a plain length of tubing or as a complete ring. In carrying out this alternative method of assembly the tube E is placed in position in the groove A¹ in the inner contact member A which then has one side thereof placed within the outer contact member D so that a portion of the tube is in position between the two contact members. The inner contact member is then gradually tilted into its correct position within the outer contact member, the tube being stretched locally during this operation where it is being passed over the lower edge of the outer contact member into the groove D¹ therein. Thus this method of assembly may be likened to the fitting of a pneumatic tyre to a wheel rim in that a portion of the tubular insulating member is first placed in position and then the rest is gradually worked into place.

In the construction illustrated in Figures 3 and 4 the switch comprises a member F formed of insulating material and secured 40 to the steering wheel boss or post G by a bolt H passing through an upper disc H¹, a hollow distance piece or sleeve H² and a lower disc H³. The member F supports a fixed annular contact member J having a 45 terminal J¹ adapted to be connected for example to one terminal K¹ of a horn indicated at K. Surrounding the sleeve H² and clamped between the upper and lower discs H¹ and H³ is a ring L of rubber or other 50 resilient insulating material, the outer edge of which has mounted thereon the boss M of an auxiliary switch operating wheel M¹. The boss M carries a movable contact ring N held in position by means of a spring 55 ring or the like N¹ and serving to maintain the boss M in position on the rubber ring L. The boss M is formed of electro-conducting material and carries a terminal M² which is connected to one terminal of a battery indicated at O in Figure 2 the other 60 terminal of which is connected to the second terminal K² of the horn K as shown.

It will be seen that by depressing the rim M³ of the wheel M¹ at any point, the rubber

ring L can be flexed and the movable contact member N brought into contact with the fixed contact member J, thus completing the horn circuit, the wheel M¹ and movable contact member N being returned to the normal inoperative position by the resilience of the rubber ring L when the rim M³ is released.

70 In the construction illustrated in Figures 5 and 6 the switch comprises an annular member P adapted to be secured to the steering wheel for example by members Q clamping it to the spokes. Mounted on the upper surface of the member P is a metallic contact ring or a series of contact segments R between which and the member P is gripped the inner edge of a rubber ring or series of rubber segments S, the number of segments being for example four or five. The outer edge of the rubber ring or of each rubber segment S is clamped by a ring T to a movable contact member U conveniently in the form of a wheel rim. Terminals R¹ and U¹ are provided respectively on the contact members R and U as shown. With this arrangement it will be seen that the rim U which also constitutes the movable contact member can be rocked by applying pressure to it at any point so as to make contact between it and the fixed contact member or members R and thus close the switch to complete the horn or other circuit. As in the construction shown in Figures 1 and 2 and in Figures 3 and 4 the rim U is returned to its normal or neutral position automatically when it is released by reason of the resilience of the rubber ring or segments S, the ring or segments S normally serving also to insulate the contact members R and U from one another.

90 100 105 110 115 120 125 130

It is to be understood that the constructional details of the switch may be varied considerably according to the purpose for which the switch is intended or to suit individual requirements without departing from this invention. Further although the invention is particularly applicable to switches for closing the horn or other circuits on motor road vehicles, it may also be applied where convenient to switches for other purposes.

What I claim as my invention and desire to secure by Letters Patent is:—

1. An electric switch including in combination two coaxial contact members, at least a portion of one member lying within the other member, said members having opposed recesses formed in these overlapping portions and resilient material disposed radially between the two members in the recesses and serving normally to maintain the contact members out of contact but to permit one to be rocked into engagement with the other when desired.

2. An electric switch including in combination two coaxial contact members, at least

- a portion of one member lying within the other member, said members having opposed recesses formed in the overlapping portions, and resilient insulating material compressed radially between the two members in the recesses thereby to maintain the contact members out of contact and to serve as the operative connection between them to prevent their being completely separated yet 10 allow further compression when one contact member is rocked into engagement with the other.
3. An electric switch including in combination two coaxial contact members, at least 15 a portion of one member lying within the other member, said members having opposed annular recesses formed in the overlapping portions, and a length of resilient insulating material disposed in the recesses so as to lie 20 radially between the two contact members and serve to maintain them normally out of contact but to permit one contact member to be rocked into engagement with the other when desired.
- 25 4. An electric switch including in combination two coaxial contact members, at least a portion of one member lying within the other member, said members having opposed annular recesses formed in the overlapping 30 portions, and a length of resilient insulating material disposed in the recesses free from positive connection with either contact member so as to lie radially between the two contact members and serve not only normally 35 to maintain them out of contact but also to serve as the sole operative connection between the contact members thereby to prevent their being completely separated but enable one contact member to be rocked into 40 engagement with the other when desired.
5. An electric switch including in combination two coaxial contact members, at least a portion of one member lying within the other member, said members having opposed 45 annular recesses formed in the overlapping portions, and a length of rubber tubing disposed in the recesses so as to lie radially between the two contact members and serve to maintain them normally out of contact 50 but to permit one contact member to be rocked into engagement with the other when desired.
6. An electric switch including in combination two coaxial contact members, at 55 least a portion of one member lying within the other member, said members having opposed annular recesses formed in the overlapping portions, and a length of rubber tubing disposed in the recesses without being 60 positively connected to either contact member so as to lie radially between the two contact members and serve not only normally to maintain them out of contact but also to serve as the sole operative connection between the contact members and 65 permit one contact member to be rocked into engagement with the other when desired.
- In testimony whereof I have signed my name to this specification.
